GOOGLES

William L. Seidel, Wyomissing, Pa., assignor to
 Willson Products, Inc., Reading, Pa., a corporation of Pennsylvania

Application March 26, 1951, Serial No. 217,487

2 Claims. (Cl. 2-14)

1

The present invention relates to improvements in goggles and, more particularly, to an adapter or eyeshield to which may be quickly attached eye-pieces of various designs or having different types of lenses for various industrial uses.

In the past, goggles have been employed formed in the shape of a plastic frame to the rim of which was sewn or attached an eyeshield for completing the goggles and for providing a light-tight enclosure as the result of a close fit between the shield and the portions of the face of the wearer surrounding the eyes. An outstanding disadvantage of such construction is that it does not enable replacement of plastic frames for protection against different work conditions, also, it does not enable substitution of different sized eyeshields so as to conform more closely to different sized faces.

An object of the present invention is to provide goggles for industrial use which are devoid of the above-named disadvantages and which are readily and easily assembled in a quickly detachable manner.

A more specific object of the invention is to provide a pair of goggles comprising separate cup-shaped, lens supporting pieces which are detachably secured to a flexible eyeshield, which shield is held by straps closely against the face of the wearer so as to positively exclude light from the eyes of the wearer irrespective of variations in contours of the face of different wearers.

Other objects and advantages of the present invention will become apparent from a study of the following description taken with the accompanying drawings wherein:

Fig. 1 is a perspective view of a pair of goggles embodying the principles of the present invention;

Fig. 2 is an enlarged, fragmentary, longitudinal cross-sectional view showing the joint between the plastic lens supporting cup and eyeshield;

Fig. 3 is an enlarged, fragmentary horizontal cross-sectional view taken substantially along line 3-3 of Fig. 1;

Fig. 4 is an enlarged fragmentary plan view of the nose surrounding portions of the lens supporting cups;

Fig. 5 is an enlarged fragmentary view of the portion of the flexible shield which surrounds and supports the parts shown in Fig. 4;

Fig. 6 is an enlarged perspective view of the nose pad shown in Figs. 1 and 3;

Fig. 7 is a side view of the nose pad shown in Fig. 6;

2

Fig. 8 is a plan view of the screw cap member and assembly shown in Figs. 1 and 3, and

Fig. 9 is a side view of the assembly shown in Fig. 8.

Referring more particularly to Figs. 1, 2 and 3 of the drawing, numerals 1 and 2 denote substantially cup-shaped members preferably made of plastic or other suitable material, and having supported thereon lenses, such as 3, by means of retaining rings, such as 4, which are screw threaded to correspondingly internally threaded portions of the cup-shaped members 1 and 2. The cup-shaped members 1 and 2 have a mouth or marginal portion which is flared outwardly and rearwardly away from the nose of the wearer so that the depth of the cup-shaped members along the temple covering portion is deeper than the portion immediately adjacent the nose. The mouth or marginal edge of each cup-shaped members 2 and 3 is turned outwardly and forms an outwardly flaring bead 5 throughout the entire periphery thereof. Bead 5 is adapted to fit into a correspondingly shaped groove 6 which is formed along the marginal edge of two eye openings formed in a shield or mask 7 made of rubber or other suitable elastic material. The depth of the shield as well as that of the cup-shaped members becomes progressively greater, flaring outwardly and rearwardly from the nose of the wearer.

An important feature of the invention is the detachable fit between the bead 5 and groove 6 of the mask throughout the entire peripheral portion of each eye-opening of the shield since it enables the quick removal or replacement of the cup-shaped eye members 1 and 2 in the event new eye members, such as those having a different type of lens or different depth, are to be substituted for those supported by the shield. In short, it is merely necessary to pull apart the cup-shaped members 1 and 2 from their frictional yieldable engagement within the slot 6 of the mask 7 which can be done simply and very quickly. Replacement is done with equal facility and speed.

Shield or mask 7 is so shaped as to closely fit the contour of the wearer's face which surrounds the eyes, the peripheral edge being somewhat thinner than the remaining portion to provide a comfortable fit. Shield 7 is held against the face by means of straps 8 which extend through slits 9 formed in the shield as well as through registering slits 10 formed near the outermost peripheral edge portions of the cup-shaped elements 1 and 2. The innermost portions of strap 8 are folded back and sewn to form thickened end portions for

anchoring them against the inner surface of the cup-shaped members. Therefore, as strap 8 is tightened about the perimeter of the head, it will exert inward pressure against the side portions of the shield 7 so as to insure a sufficiently close fit so as to exclude the entry of light into the interior of the goggles and prevent the shield from being detached too easily when worn.

As shown more clearly in Fig. 4, the lens rims of cup-shaped elements 1 and 2 have integral, inwardly extending bridge portions 11 and 12 which have slits 13 extending therethrough. Corresponding slits 14 are provided in the nose bridging portion of shield 7, as shown in Fig. 5, which will be in registry with slits 13 when the cup-shaped members are attached to shield 7. A nose pad 15 is provided, as shown in Figs. 6 and 7, which is made of felt, leather or other suitable material, and which has integral extensions 15a which are slid through the registering slots 13 and 14, as shown more clearly in Fig. 3, and which finally emerge through corresponding registering slots 17a formed in a plate 17 to which plate is integrally secured screw stud 16. Thus, by screwing an internally threaded cap member 18 on the stud 16, the base portion thereof will clampingly engage the ears or extensions 15a between it and plate 17 and thereby lock the parts in assembled relationship.

Of course, pad 15, plate 17, stud 16 and screw cap 18 may be omitted under certain circumstances wherein locking of the parts is not deemed indispensable.

Thus it will be seen that there is provided in accordance with the present invention, an efficient pair of goggles comprising an assembly of parts that are quickly detachable or attachable to allow a wide variety of substitutions, such as different designs of goggle cup-shaped members or of different types of goggle lenses, to make the goggles flexible and adaptable for a wide variety of industrial uses.

While I have illustrated and described one specific embodiment of my invention, it will be understood that this is by way of illustration only, and that various changes and modifications may be made within the contemplation of my invention and within the scope of the following claims.

I claim:

1. A pair of goggles comprising, in combination, a pair of cup-shaped lens supporting members having disposed about each of their mouth portions a substantially radially and outwardly extending bead, said mouth portions flaring outwardly and rearwardly from the portion of said cup-shaped members closest to the nose of the wearer, a flexible shield having a pair of openings of the same contour as the mouth portions of said cup-shaped members, a groove disposed about the periphery of each of said openings

and being shaped and flared so as to receive and closely fit said beads in tight frictional relationship to enable said cup-shaped members to be quickly attachable in assembled relationship with said shield and quickly detachable therefrom, thereby permitting ready replacement of the parts of the goggle assembly, said cup-shaped members have ear-like extensions, each adapted to surround half of the top portion of the nose of the wearer, each of said extensions having a slot, slots corresponding to and in registry with the last-mentioned slots formed in a nose bridging portion of said shield, a screw threaded stud having a base plate containing slots in registry with both of said registering pairs of slots, a nose pad having a pair of ears extending therefrom which extend through all of said registering slots and having extremities thereof extending outwardly of the bridge portion of said shield, and a screw threaded cap in threaded engagement with said stud for clamping said pad extensions between it and said base plate so as to securely lock all of the parts of said goggles in assembled relationship.

2. A pair of goggles comprising outwardly and rearwardly flared cup-shaped lens supporting portions of hard material each having a side temple covering portion, a light-shielding mask of resilient material and having a pair of openings whose perimetrical portions have grooves so shaped as to detachably, frictionally and yieldably receive the mouth portions of said lens supporting portions, the outer rim portion of said light-shielding mask being shaped so as to closely fit the contour of the face portion surrounding the eyes of the wearer, a slot provided in the sides, temple-covering portion of each of said cup-shaped lens supporting portions, and strap means having portions which engage the outside surface of the temple-covering portions of said mask and extend through said slots and terminate in enlarged end portions which are larger than the slots, so that as said strap means is tightened, it will press said temple-covering portions of the mask against the temples of the wearer to insure a secure and light-excluding fit of the mask.

WILLIAM L. SEIDEL.
